UNITED STATES PATENT OFFICE

169,575

ELECTRIC DEEP FAT FRIER

Stanley J. Budlane, Palatine, and Robert Dusek,
Cicero, Ill., assignors to Dulane, Inc., River
Grove, Ill., a corporation of Illinois

Application August 25, 1952, Serial No. 21,186

Term of patent 14 years

(Cl. D81—10)

To all whom it may concern:

Be it known that we, Stanley J. Budlane and Robert Dusek, citizens of the United States and residents, respectively, of Palatine, county of Cook, State of Illinois, and Cicero, county of Cook, State of Illinois, have invented a new, original, and ornamental Design for an Electric Deep Fat Frier, of which the following is a specification, reference being had to the accompanying drawing, forming a part thereof, in which:

Figure 1 is a side elevational view of the electric deep fat frier embodying our new design;

Figure 2 is a front view thereof;

Figure 3 is a back view thereof;

Figure 4 is a top view of the electric deep fat frier with the lid in position; and

Figure 5 is a top view without the lid.

We claim:

The ornamental design for an electric deep fat frier, substantially as shown.

STANLEY J. BUDLANE.
ROBERT DUSEK.
